UNITED STATES PATENT OFFICE.

WILLIAM J. GAGNON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

CHAIN-PENDANT.

1,083,821.

Specification of Letters Patent.

Patented Jan. 6, 1914.

Application filed October 28, 1913. Serial No. 797,808.

To all whom it may concern:

Be it known that I, WILLIAM J. GAGNON, a citizen of the United States of America, residing in the city of Bridgeport, county 5 of Fairfield, and State of Connecticut, have invented certain new and useful Improvements in Chain-Pendants, of which the following is a specification.

The invention relates to chain pendants, 10 and particularly to the pendant for chains of the type commonly used for operating electric pull switches.

A particular object of my invention is to provide a pendant which, after installation, 15 is readily adjusted to a different length of chain.

In the accompanying drawings, Figure 1 is a side elevation of an electric pull switch on the chain of which my improved pendant 20 is shown in side elevation; Fig. 2 is a vertical section through the pendant; Fig. 3 is an inverted plan thereof; Fig. 4 is a side elevation showing the pendant during the adjustment thereof on the chain; Fig. 5 is a 25 side elevation of a lengthened chain to which my pendant is attached.

In the particular form here shown, my improved pendant comprises a spherical body comprising upper and lower hemispheres 10 and 11 respectively and an interposed diaphragm 12 (Fig. 2), for giving added rigidity to the construction. The upper hemisphere is centrally apertured at 13 to a diameter slightly greater than that of 30 the balls 14 of the chain on which the pendant is designed for adjustment. The lower hemisphere 11 is centrally perforated to a diameter somewhat less than the diameter of the balls 14 and is radially slit at 16 to 35 form a plurality of spring fingers 17. The peripheral edge of the hemisphere 11 is slightly outturned at 18 to form an engaging shoulder beneath which the outturned edge 19 of the hemisphere 10 may be spun 40 to hold the two parts together. To strengthen the pendant, the diaphragm 12 is arranged between the adjacent edges of 45 the two hemispheres and is held in place by

the spun over edge 19. This diaphragm is centrally apertured at 20 to permit the balls 50 14 to pass freely therethrough.

To position the pendant on the chain, it is only necessary to pass the terminal ball 14^a of the chain freely through the apertures 13 and 20 of the hemisphere 10 and diaphragm 55 12 respectively, and then force it through the aperture 15 of the hemisphere 11, the spring fingers 17 of the latter spreading slightly (Fig. 4) as the ball passes through. As soon as the ball 14^a has passed through 60 the aperture 15, the spring fingers retract to their normal position, and inasmuch as the aperture 15 is of less diameter than the ball 14^a, a downward pull upon the pendant serves merely to press this ball against the 65 outer faces of the ends of the spring fingers 17, thus forcing them the more closely together and constricting the aperture 15 so that there is no possibility of the ball escaping through the pendant. 70

If it is desired to shorten the chain, the pendant is merely forced up over successive balls on the chain until it has reached the desired position, whereupon the chain extending beyond the ball may be cut off. On 75 the contrary, when the chain is to be lengthened, the terminal ball 14^a may be cut off, and the pendant adjusted upon the end of the added length of chain, the other end of which is attached to the original piece by a 80 coupling attachment 21 of any suitable construction.

I claim as my invention:—

1. A chain pendant comprising a hollow body having apertures in vertical alinement, 85 the upper aperture being of greater diameter than the lower, and the body of the pendant surrounding the lower aperture being slotted to form spring fingers, substantially as and for the purpose described. 90

2. A chain pendant comprising a hollow spherical body having upper and lower hemispheres with interengaged edges and a transverse diaphragm seated between said edges and serving as a stiffener, said members being apertured in vertical register, the 95

apertures in the diaphragm and upper hemisphere exceeding in diameter the aperture in the lower hemisphere, said lower hemisphere being slotted around the aperture therein to form a series of spring fingers, substantially as described.

In testimony whereof I have signed my

name to this specification, in the presence of two subscribing witnesses.

WILLIAM J. GAGNON.
